UNITED STATES PATENT OFFICE.

ROLAND DANE PARKS, OF LAKE LINDEN, MICHIGAN.

YIELDABLE SUPPORT.

Application filed February 18, 1926. Serial No. 89,124.

The device of the present invention while capable of a wide field of utility, is primarily designed for withstanding subsidence pressures in subterranean mining operations.

5 An object of the invention is to provide a metal support or column adapted to take the place of the supporting timbers usually employed.

10 A further object of the invention is to provide a yielding support of this character embodying a yieldable or strainable element which becomes distorted under excessive pressures without distorting or twisting the main body of the column or support.

15 A further object of the invention is to provide a device of the class described which will be of rugged, durable, practical construction, which will be highly efficient and capable of repeated use, and which may be 20 manufactured with comparative economy.

In carrying out the invention I prefer to employ a plurality of metallic members capable of a relative sliding action when an intermediate yielding member is strained by 25 pressures on the relatively movable members.

30 Preferably the strainable element is capable of ready removal and replacement so that undue pressures on the column can result in rendering useless only the strainable element without impairing the further usefulness, or in any way injuring the telescoping or relatively sliding members.

With the above noted and other objects in view, the invention consists in certain novel 35 features of construction and combinations and arrangements of parts, as will be more fully hereinafter set forth and pointed out in the claims. The invention may be more fully understood from the following description in connection with the accompanying drawings, wherein—

40 Fig. 1 is a broken view in front elevation of a supporting column embodying the invention.

45 Fig. 2 is a view in longitudinal section therethrough on the line 2—2 of Fig. 1.

Fig. 3 is a view in transverse section on the line 3—3 of Fig. 1.

50 Fig. 4 is a perspective view of the strainable element.

Figs. 5 and 6 are side elevational views of the cutting implements.

Fig. 7 is an enlarged edge view of the element shown in Fig. 4.

55 The problems involved in withstanding the subsidence pressures in subterranean

mining operations are too well recognized to warrant a lengthy discussion, but it may be briefly noted that the only type of support which has heretofore been considered practical, has been a wooden strut which is inherently compressible under pressure. The function of an efficient mine support is not to rigidly support its load, but rather to yield with the load and so keep the passageways open for a long enough period of time in which to effect the necessary operations of mining. The movement of subsiding ground is slow, but irresistible. Hence, the time element is vital and can be furnished only by a support of a yieldable nature which will "give" under excessive loadings, thereby allowing a natural arch to form and carry the greater portion of the subsidence pressure. Relatively non-yielding metallic supports, as they have heretofore been installed with rigidity and strength as the objective become hopelessly deformed and twisted, block the underground passageways, and are difficult to remove after distortion.

In accordance with the present invention, I provide a yieldable metallic column or strut in which the distortion caused by subsidence pressures acts to telescope the column without distorting any part thereof, except a strainable element which may be readily removed and replaced.

In the accompanying drawings I have used the reference numeral 10 to designate an I-beam which serves as the base of the column. A pair of oppositely facing channel bars 11 are secured together in back to back relationship, the flanges 11^a of the channels being accommodated between the flanges or heads 10^a of the I-beam. It will be noted that the channel members 11 are spaced apart for disposition upon the opposite sides of the I-beam. Preferably the upper ends of both channel members 11 are bolted to a spacer plate 12, and the upper portion of the I-beam 10 which is received between the channel members may be supplemented by spacer plates 13, so that the channel members have a sliding fit on the I-beam.

The channel members are provided with slots 14 and 15 aligned respectively with slots 16 and 17 in the I-beam. Bolts 18 pass through the aligned slots 14, 16 and bolts 19 pass through the aligned slots 15, 17, guide the relative sliding movement of the channel members and the I-beam. It will be noted

that the slots 14 are relatively short, and the slots 16 relatively long, and also the slots 15 are relatively long, while the slots 17 are relatively short. However, the effective relative sliding permitted by each set of slots is the same. By forming the channel members and the I-beam each with a set of short slots, and a set of long slots, I preserve the maximum strength in both the channel members 10 and the I-beam, while obtaining a maximum amount of relative sliding movement.

It will be evident that by tightening the bolts 18 and 19, the members 10 and 11 may be firmly clamped together so that they will create a large frictional resistance to relative sliding of the members. Merely overcoming this frictional resistance however, will not effect collapsing of the support. The yieldable element is in the nature of a plate 20 of soft metal or metallic alloy which is interposed between the top of the I-beam 10 and a set of transversely mounted cutting tools 21 supported adjacent thereto by the upper ends of the channel members 11. It will be noted that the yieldable or strainable member 20 is formed with a plurality of grooves 22 extending longitudinally thereof to provide relatively thin weakened portions 23 in the path of the cutting tools.

30 When the column has been set up in a tunnel, and subsidence pressures become great enough to overcome the friction between members 10 and 11, plus the resistance offered by the ultimate strength of the metal 35 in the path of the cutting tools, there will be a relative sliding movement or telescoping action of the members 10 and 11. Cutting tools 21 pass downwardly through the weakened portions 23 of the strainable element 40 20, cutting through these portions and cutting or extruding the metal therefrom. Slots 25 are provided in the channel bars for the escape of metal forced outwardly by the cutting tools.

45 From the foregoing description it will be evident that I have provided for considerable yielding of the column without injury to any portion thereof, except the member 20, so that there is no danger of distorting the body 50 of the column. By disassembling the sliding elements of the column, the strained member 20 may be readily removed and replaced and the column reused.

55 I have shown a strainable element subject to distortion under compression, but it will be obvious that this element might be arranged for distortion when the column is placed under tension, that it might in some instances be distorted by excessive torque exerted on relatively rotating members, and

that it also might be distorted under shearing strains or stresses.

It will also be obvious that various types of supports embodying the principle of the present invention may prove useful in other fields than underground mining operations. In fact, devices embodying the invention are suitable for use wherever yielding struts, trusses or braces are desirable.

Various changes and alterations might be 70 made in the general form and arrangement of parts described, without departing from the invention. Hence I do not wish to limit myself to the details set forth, but shall consider myself at liberty to make such changes 75 and alterations as fairly fall within the spirit and scope of the appended claims.

I claim—

1. A support of the class described including an I-beam, spaced oppositely facing channel members straddling the I-beam and mounted for limited sliding movement relative thereto, a metallic element adapted to be strained, normally blocking sliding movement of the channel members relative to the I-beam, and means carried by the channel elements acting on the member to be strained to distort the same and render the same inoperative when excessive loads are imposed 90 on the channel members.

2. In a support of the class described, an I-beam, oppositely facing spaced channel members straddling the I-beam and having limited sliding movement relative thereto, a soft metallic plate between the channel members opposing sliding movement of the channel members relative to the I-beam, and cutting elements associated with the channel members for straining the soft metal plate to permit such sliding movement.

3. In a support of the class described, an I-beam, oppositely facing spaced channel members straddling the I-beam and having limited sliding movement relative thereto, a soft metallic plate between the channel members opposing sliding movement of the channel members relative to the I-beam, and cutting elements associated with the channel members for straining the soft metal plate to permit such sliding movement, said soft metal plate being formed with weakened portions in the path of movement of said cutting elements.

4. A device of the class described in claim 2, and wherein the channel members and I-beam are formed with aligned slots, and bolts in said slots guide the sliding movement of the members.
